[57] CLAIM

The ornamental design for a combined jumper cable control box and lamp, substantially as shown and described.

DESCRIPTION

FIG. 1 is a perspective view of a combined jumper cable control box and lamp, with associated cables and terminal clamps being shown in broken lines for illustrative purposes only and forms no part of the claimed design;

FIG. 2 is a top plan view thereof;

FIG. 3 is a side elevational view thereof, the two sides being substantially identical;

FIG. 4 is a bottom plan view thereof;

FIG. 5 is a front elevational view thereof;

FIG. 6 is a rear elevational view thereof.
